CLAIM

The ornamental design for a display screen with graphical user interface for negative pressure unit, as shown and described.

DESCRIPTION

This invention was made with government support under Contract FA8650-13-2-6372 awarded by the Department of the Air Force. The government has certain rights in the invention.

FIG. 1 is an upper front isometric view of a display screen with graphical user interface for negative pressure unit;

FIG. 2 is a front view thereof.

FIG. 3 is a rear view thereof.

FIG. 4 is a first side view thereof.

FIG. 5 is a second side view thereof.

FIG. 6 is a top view thereof; and,

FIG. 7 is a bottom view thereof.

The broken lines in the Figures depict portions of the display screen with graphical user interface for negative pressure unit that form no part of the claimed design.
